poration of New York

Application November 18, 1944, Serial No. 564,151

18 Claims. (Cl. 161—232)

1

This invention relates to a combination printing machine and oven drive and more particularly to a drive mechanism and the controls therefor, whereby a printing machine and a device for conveying printed matter to and through a drying oven, may be operated independently by separate driving means or brought into synchronism and operated simultaneously by the printing machine drive.

In a drive mechanism of this nature it is desirable that provision be made whereby the printing machine may be operated independently for make-ready or for independent printing purposes, and whereby the oven feed may be operated independently to clear the oven after a run is completed, and also that provision be made whereby, upon stopping of the oven feed, the printing operation will be automatically interrupted and the printing machine driven at a slow idling speed.

To obtain this desiderata it is contemplated as the principal object of the invention to provide mechanical and electrical protective interlocks in the structure of the drive whereby sheets will not be fed to the printing machine nor to the oven until the press feed and the oven feed are in synchronism, that is, until the printing machine feed and the oven feed are in proper timed relation.

Another object of the invention is to provide in a drive of the above nature, an improved form of synchronizing device whereby the printing machine delivery and the oven feed may be automatically synchronized.

A further object of the invention is to provide in a drive mechanism suitable interlocks in the structure and controls thereof whereby stopping of the printing machine will immediately disconnect the oven drive from the machine drive and cause continued operation of the oven feed, whereby the oven feed cannot be connected to the machine drive unless the sheet conveyors are in proper operable position, and whereby, if the oven feed is stopped, the feeding of sheets to the machine will stop, a device to stop sheets feeding to the oven will be actuated, and the machine will continue running at a slow idling speed.

It is also an object of the invention to provide a combination printing machine and oven drive of generally improved construction whereby the mechanism will be simple, durable, and relatively inexpensive in construction, as well as convenient, practical, serviceable, and efficient in use.

With the foregoing and other objects in view, which will appear as the description proceeds, the

2

invention resides in the combination and arrangement of parts, and in the details of construction hereinafter described and claimed.

The preferred embodiment of the invention is illustrated in the accompanying drawings, wherein:

10 Figure 1 is a side view of a combination printing machine and oven drive, shown in operative association with a printing machine and oven feed, in which the features and principles of the invention are embodied;

15 Figure 2 is an enlarged top plan view of the printing machine driving motor and of the synchronizing device between it and the oven drive;

15 Figure 3 is a sectional view taken on the line 3—3 of Figure 2;

Figure 4 is a sectional view taken on the line 4—4 of Figure 3;

20 Figure 5 is an enlarged sectional view taken on the line 5—5 of Figure 2;

Figure 6 is a sectional view taken on the line 6—6 of Figure 5 with a portion broken away;

Figure 7 is a diagram of the electrical controls for the drive of this invention; and

25 Figure 8 is a representation of a selector switch.

The machine illustrated in Figure 1, is a two-color offset printing machine, designed for printing on sheet metal and having plate or form cylinders 11 and 12, a blanket cylinder 13 and an impression cylinder 14, which cylinders are operable in the usual manner by suitable gearing (not shown) but connected to a drive shaft 15 having a chain driven pulley 16 secured thereto.

30 As is usual in printing machines of this type a cylinder tripping mechanism (not shown) is provided which is actuated to trip the cylinders whenever there is an interruption in the proper feeding of sheets. It will be understood that the

35 machine illustrated is also provided with suitable means (not shown) for separating the sheets from a pile and feeding them to the printing cylinders 13 and 14. This means may include suction devices actuated by solenoids 17 which are controlled by a feeder switch 18 and are electrically interlocked with the drive control circuit.

40 The sheets are conveyed from the printing machine to a coating machine 19, by conveyor belts 23 and thence by conveyor belts 24 to an oven conveyor comprising a plurality of wickets 22 attached to an endless chain conveyor 23 by which the printed sheets are carried through a suitable drying oven 24. The conveyor 23 is driven by a chain pulley 25 secured on a shaft

45 26 having a bevel gear 27 in mesh with a bevel

50 28 having a bevel gear 29 in mesh with a bevel

gear 28 secured on a vertical shaft 29 which extends downward to a lower floor level, where it is connected to an oven drive unit having suitable gearing in a casing 30, and connected to a horizontal motor shaft 31 operated by a motor 32. The coating machine 19 is driven from the shaft 29 by bevel gears 29a and 29b, a horizontal shaft 29c, bevel gears 29d and 29e and a vertical shaft 29f.

The shaft 31 is connected through a chain pulley 33, a chain belt 34 and a chain pulley 35, to a horizontal shaft 36 which extends from the oven drive unit, to a synchronizing device and a printing machine drive unit shown in Figure 1 and more in detail in Figures 2-6 inclusive. This drive unit (Figure 2) is below the printing machine and comprises a motor 37 having a chain pulley 38 on its shaft 39. The pulley 38 is connected by a chain belt 40 to the chain pulley 16 (Figure 1) to drive the press.

Referring now to Figures 2-6 inclusive, the shaft 36, from the oven driving unit, enters a gear box 41, (Figure 2), and is connected to a shaft 42, through bevel gears 43 and 44, secured to shafts 36 and 42 respectively. The shaft 42 extends into a differential gear box 45 and has a gear 46 secured thereto. The gear 46 is in mesh with a gear ring 47 which is secured to and carried by a hub member 48 rotatably mounted upon a shaft 49 (Figures 3 and 4). The shaft 49 extends from the gear box 45 and is secured to one part 51 (Figure 2) of a magnetic clutch, the other part 52 of which is connected to an end 53 of the motor shaft 39. Thus by operation of the motor 37 the press may be driven, and by operation of the motor 32 the oven feed may be driven, each independently of the other, provided the magnetic clutch 51, 52 is deenergized. Also, the oven conveyor may be driven by the press motor 37, by engaging the magnetic clutch parts 51 and 52, and deenergizing the oven conveyor motor 32. Before engaging the magnetic clutch, however, it is necessary that the oven and the printing machine be properly synchronized, to insure the arrival of each sheet at the oven, in an instant when a wicket 22 is in position to receive it.

The synchronizing mechanism herein disclosed includes a differential gearing (Figures 3 and 4) comprising a pinion 54 secured to the shaft 49, and meshing with pinions 55, 56, and 57 rotatable on the stud shafts 58, 59, and 61 respectively. The stud shafts 58, 59 and 61 are carried by and extend from a worm gear 62 which has a hub 63 in which the shaft 49 is journaled. The hub 63 is in turn journaled in a bearing 64 provided in a wall of the gear box 45. The teeth of the pinions 55, 56, and 57 are also in mesh with internal gear teeth formed on the inner periphery of the gear ring 47. The outer periphery of the gear body 62 is provided with worm teeth 65 thus providing a worm wheel 66 to mesh with a worm gear 67.

Rotation of the worm gear 67 acting through the differential gearing described will position the shaft 49 in respect to the shaft 36 so that proper delivery of the sheets from the press to the wickets 22 may be accomplished after the magnetic clutch 51, 52 is energized to cause the press motor 37 to drive the oven conveyor. The worm gear 67 may be rotated, by a timing motor 68 through a shaft 69 to which the gear 67 is secured. The motor 68 is under the control of a timing switch 71, arranged to be actuated to start and stop the motor 68 by means of a synchronizing detector (Figures 5 and 6) that operates to

insure that the machine drive and the oven drive are in proper timed relation. The motor 68 is mounted on a bracket 72 extending from the gear box 45.

The synchronizing detector includes an operating disc 73 (Figure 2) carried by a sleeve 74 which is mounted on a shaft 75 for sliding movement axially thereof. The disc 73 is arranged to have one of its sides contact an operating lever 76 of the timing switch 71. The disc 73 is constantly urged in one direction along the shaft 75 by a spring 77 coiled about the shaft 75 and reacting between the sleeve 74 and a collar 78 secured to the shaft 75. A hub member 79 formed integral with the disc 73 extends therefrom on the side opposite to that engaging the switch lever 76. A disc actuating arm 81 (Figures 5 and 6), which is bifurcated at its free end to straddle the shaft 75 and to form fingers 82 and 83 positioned to engage the end of the hub member 79, is pivoted by a pin 84 in and between brackets 85 and 86. The brackets 85 and 86 are secured to, and thus carried by, a disc 87 which is secured to the shaft 75 by a set screw 88. A stud 89 extends from the arm 81 through an opening 91 provided in the disc 87 and has a roller 92 mounted upon its outer end. The roller 92 is arranged to ride upon the inner periphery of an enlarged circular opening 93 provided in a circular plate 94. At one point in the periphery of the opening 93 an arcuate depression 95 is formed, into which the roller 92 will drop when it is opposite the depression 95, due to relative rotation of the disc 87 and the plate 94. The roller 92 dropping into the depression 95 allows the arm 81 to swing on its pivot pin 84 whereby the hub 79 and the disc 73 under the urge of the spring 77, will move along the shaft 75 and allow the timing switch 71 to operate, first to stop the motor 68 and then to close a circuit energizing sheet feeding control devices as hereinafter disclosed.

The plate 94 is provided with a peripheral flange 96 which overlaps the periphery of a disc 97 and is adjustably secured thereto by washers 98 overlapping the outer edge of the disc 97 and held by means of screws 99, thus clamping the disc 97 to an annular shoulder 101 provided on the flange 96. The disc 97 is provided with a hub 102 which is secured to a shaft 103 by a set screw 104. The disc 97 is recessed at 105 to receive an end of the shaft 75 in a ball bearing 106 mounted in the recess 105. Annular adjustment of the plate flange 96 upon the disc 97 permits the positioning of the depression 95 in respect to the roller 92 to time the action of the disc 73 upon the switch lever 76 in respect to the relative rotation of the shafts 75 and 103.

The shaft 75 is connected by a coupling 107 (Figure 2) to a stud shaft 108 extending from a reduction gear housing 109, the gears therein (not shown) being driven from a sprocket wheel 111 which in turn is driven from a sprocket wheel 112 by a chain 113. The sprocket wheel 112 is secured upon an end 114 of the shaft 42 which extends beyond the gear box 45. The shaft 103 extends into a reduction gear housing 115 the gears therein (not shown) being driven by a sprocket wheel 116 which in turn is driven from a sprocket wheel 117 by a chain 118, the sprocket wheel 117 being secured to the extended end 53 of the press motor shaft 39. A pulley 119, connected to and rotatable with the sprocket wheel 111, is drivingly connected to a pulley 120 by a belt 121. The pulley 120 is connected to a

centrifugal switch 122 (Figure 7) disposed in a housing 123 and connected in a control circuit for the magnetic clutch 51, 52. A similar centrifugal switch 124 (Figure 7), disposed in a housing 125 is connected to a pulley 126 which is drivingly connected to a pulley 127 by a belt 128. The pulley 127 is drivingly connected to the sprocket 116. The centrifugal switch 124 in the housing 125 is in the aforementioned magnetic clutch control circuit and is in series with the centrifugal switch 122 in the housing 123 (Figure 7).

The sheet conveyor belts 29 may be swung upward to give access to the coater 19. Such movement operates a double throw conveyor switch 129 (Figures 1 and 7), which prevents coupling the press drive to the oven conveyor drive, and permits hand feeding of sheets to the coating machine and forwarding them to the oven, and also permits operation of the printing machine separately to print and stack sheets that do not require baking. A sheet stopping device 131 also is provided and is located adjacent the coater 19. Preferably the device 131 comprises a plurality of fingers which are arranged to be swung upwardly into the path of the sheets by a spring and to be drawn downward to the position in Figure 1 by means of a solenoid 132 (Figure 7).

From the foregoing paragraphs it will be understood that the printing machine and the oven conveyor have individual motors, and a three element differential gear mechanism (Figures 3 and 4) is provided having driving connections to the printing machine motor 37, to the oven conveyor motor 32, and to the timing motor 68. The clutch 51—52 is interposed between the motor 37 and the differential gear mechanism, so when the clutch is disengaged, one of the differential driving connections is broken, and the printing machine and the oven conveyor can be operated separately. In the usual operation of the equipment the machine and the conveyor are started separately and when ready to print sheets, the clutch is engaged coupling them together. Simultaneously the electrical connections to the motor 32 are broken and the printing machine, and the oven conveyor are both driven by the motor 37. The timing motor 68 operating through the differential gear then automatically brings the conveyor into proper timed relation with the machine and the timing motor is then stopped. At this time the sheet feeding mechanism is actuated and printing starts. Whenever the printing machine is stopped the clutch is disengaged and the motor 32 is energized to continue the operation of the oven so that the sheets then in the oven will remain there only the normal length of time, as is necessary to avoid spoilage. Should the oven motor be stopped while the printing machine is running, the latter will continue to run at slow speed, but the sheet feeding mechanism will stop feeding the sheets. The centrifugal switches 122 and 124 which are connected to the oven drive and the printing machine respectively and are closed only while they are running, insure that both the printing machine and the oven drive are running before the clutch is engaged. These and other electrical interlocks which are provided, prevent improper use of the equipment, as will be understood by those versed in the art.

Figure 7 shows an electrical circuit diagram with control switches in position to synchronize the oven drive and the machine drive and to operate both the printing machine and the oven

to print sheets and carry them through the oven. To operate the machine a six pole double throw manually operated selector shown in Figure 8, and having switches 133, 134, 135, 136, 137 and 138 is thrown to the right; a position in which the switches 133, 134, 135, 136, and 138 are closed and the switch 137 is open. The oven drive may now be started by closing the run button switch 139 and momentarily pressing the start button, which closes the contacts 147 and thereby energizes the coil of a relay 142 through a circuit extending from the line L2 through the run switch 139, closed contacts 146 of relay 149, contacts 147 closed momentarily by the opening of switch 141, coil of relay 142, and to the line L1. Contacts 143 (now closed), bridge the contacts 147 and maintain the coil of relay 142 energized. Energizing the relay 142 also closes the contacts 144 and energizes a coil 145 of the oven drive motor controller starting the motor and driving the chain 23 carrying the wickets 22.

The printing machine drive motor 37 may now be started by operating a start button 148 of the printing machine control. This momentarily energizes the coil of a relay 149 by a circuit from line L2 through normally closed contacts 151 of a stop button, thence through contacts 148, and coil 149, to the line L1. Energizing the coil of relay 149 closes contacts 152 to energize the coil of a relay 153 by a circuit from line wire L2 through the contacts 151, 152, and coil of relay 153 to the line L1. The coil of relay 153 is maintained energized by the closing of its contacts 154 to close a circuit from line L2 through contacts 151, 154, coil of relay 153 to the line L1. The operation of the start button 148 also energizes the control circuit of a suitable printing machine motor controller 155. Contacts 156 which are closed by the closing of the oven conveyor run switch 138, are in parallel with the contacts of switch 139 which is in its open position as shown, whenever the printing machine and oven conveyor are to be operated in synchronism. The two switches 156 and 166 are in parallel, and in series with the press drive slow-fast switch 157. When both switches 156 and 166 are open the press will run at a slow idling speed with the oven conveyor disconnected from the press and no sheets being fed. With switch 156 closed and the press drive slow-fast switch 157 open, the same idling speed is obtainable with the oven connected to the press and sheets being fed.

Momentary energization of the coil of the relay 149 also closes contacts 158 whereby a circuit from line wire L2 through run button switch 139, through normally closed contacts of the start switch 141, switch 133, contacts 158, switch 134, the coil of a relay 159, to the line wire L1. The momentary energization of the coil of relay 159, closes its contacts 161 to maintain it through a circuit leading from line L2 through switch 139, contacts 161 and 162 (then closed), contacts 161, switch 134, coil of relay 159 to line L1. The coil of a time-delay relay 163 is in parallel with the coil of the relay 159 and is therefore energized and maintained therewith.

Simultaneously with the closing of the maintaining contacts 161, the contacts 146 are opened and deenergize the coil of relay 142, opening the oven drive contacts 144 and deenergizing the coil 145 of the controller for the oven motor 32. The motor will continue to run for some time at sufficient speed, however, to maintain closed the centrifugal switch 122, which is driven by it. At

the same time other normally closed contacts 164 on the relay 159 are opened and contacts 166 on the time delay relay 163 are closed.

Before the speed of the oven drive has been reduced sufficiently to open the centrifugal switch 122, the machine drive has attained sufficient speed to close its associated centrifugal switch 124. With the conveyor belts 20, in position to convey sheets from the machine to the coater 19 and thence to the oven, the contacts 167 of the conveyor switch 129 are closed, hence closing of the contacts 165 of relay 159, completes a circuit from the line wire L2 through the run switch 139, contacts 141, 162, 161, and 165, centrifugal switches 122 and 124, conveyor switch 15 contacts 167, and through a switch 135 to energize the coil of a relay 168 connected to the line L1.

Energizing the coil of the relay 168 closes contacts 169 which complete a circuit from a direct current line DC1 through the coil of a relay 171 to a direct current line DC2. Energizing the relay 171 closes contacts 172 and energizes the magnetic clutch 51, 52 from the line DC1 and DC2, connecting the oven drive to the machine drive, both of which are then driven by the motor 37. Contacts 173 of the relay 168 are also closed and complete a circuit from line L2 through the timing switch 71, to a contactor coil 174 controlling the timing motor 68, and to the line L1 thereby starting the timing motor. When the machine feed and the wickets 22 are brought into synchronization by operation of the motor 68 and the differential gearing, and this condition is detected by the synchronizing detector, as hereinbefore described, the timing switch 71 is actuated to open the circuit to the contactor coil 174 and stop the motor 68. The timing switch 71 when so actuated closes a circuit from the line wire L2 through normally open contacts 173, now closed by the relay 168, to a normally closed contact 176, controlled by the relay 142, to a switch 136, through the coil of a relay 177 to the line wire L1. Energization of the relay 177 closes contacts 178 and 179 which control the sheet feeding control solenoid 17 and the sheet stopping control solenoid 132 respectively. Sheets may now be fed into the machine, printed thereon, passed through the coater 19 and conveyed to the wickets 22, which wickets are running in synchronization with the machine.

The equipment is ordinarily controlled by two operators, one for the printing machine and one for the oven conveyor, and the control arrangement is such that neither can stop the portion of the equipment controlled by the other operator.

To stop the printing machine without stopping the oven drive while they are running together, the push-button 151 is operated and stops the feeder and the printing machine, by opening the maintaining circuit to the relay 153, deenergizing the time delay relay 163, the relay 159, and the relay 168. Deenergizing the relay 168 opens the magnetic clutch contacts 169, disconnecting the oven drive from the machine drive; and the circuit to the relay 171 is opened, thereby deenergizing the solenoids 17 and 132, stopping the feeding of sheets, and allowing the fingers of the stopping device 131 to raise and prevent any sheets that may be on the belts 21 from reaching the oven. When the relay 159 is deenergized contacts 146 and 164 close. The contacts 166 of the time delay relay 163 remain closed for a short time after it is deenergized to insure energizing the relay 142, which will be maintained by the

5 closing of contacts 143, and the contactor coil 145 of the oven drive motor 32 will be energized by the closing of the contacts 144. Continuance of oven drive operation after the printing machine is stopped, clears the oven of sheets.

To stop the oven conveyor drive while the printing machine and oven drives are running together, the oven drive push-button switch 139 is operated. This stops the oven conveyor and the sheet feeder, but the cylinders of the printing machine will continue to rotate. Opening the switch 139 opens all circuits controlling the oven drive, the relay 142, the oven controller contactor 145, the time delay relay 163, the relay 159, the relay 168, the magnetic clutch relay 171, the relay 177, the sheet feeder solenoid 17, and the sheet stop solenoid 132, none of which can again be energized until the switch 139 is closed. The contacts 156 that are opened simultaneously with those of the switch 139 are in the slow-fast circuit of the machine drive motor which is thus decelerated to slow speed. Simultaneous with the stopping of the oven, the switch 181 opens, thereby deenergizing a slow down relay 182 which inserts a light load resistance into the circuit of the motor driving the printing machine. At all times the relay 182 is energized, its contacts short out this resistance so the machine will not stall while driving the oven.

When it is desired to run the press and oven drives independently of each other, the six pole selector switch is thrown to the left, so the contacts at poles 133, 134, 135, 136 and 138 are open and the contact at pole 137 is closed. The conveyor belts 20 being raised, the contacts 164 of the conveyor switch 129 are closed. These contacts 164 are in series with the switch 137 (now closed), whereby a feeder switch 135, when closed, will cause the relay 177 to be energized to close contacts 178 and 179 and energize the feeder solenoid 17 and the sheet stopping control solenoid 132.

To operate the printing machine alone, the switch 186 is closed. The printing machine may now be started by momentarily pressing the start button 148.

The oven conveyor may be operated separately by closing the run button switch 139 and momentarily closing the start button 141 to close contacts 147. Closing of the contacts 147 energizes the relay 142 to close the relay maintaining contact 143 and the contacts 144 to energize the control coil 145 of the oven drive motor 32. As the selector switches 133 and 134 are open, the relays 50 159 and 163 cannot be energized.

The contacts 162 provide an interlock between the machine drive controls, the oven drive controls and the synchronizing mechanism whereby the machine motor 37 must be in operation before the oven drive can be connected to it. The timing switch 71 also forms an interlock whereby the machine feed and the wickets 22 must be in synchronization before sheets can be fed. The contacts 162 also provide an interlock whereby, should the machine be stopped, the oven drive will immediately be disconnected from the press drive and operate independently to clear sheets from the oven. The conveyor switch 129 provides an interlock whereby the conveyor must be in proper sheet conveying position before the oven drive can be connected to the press drive. The switch 71 also forms an interlock to prevent sheets being fed to the press and to the oven if the oven feed is stopped or if the oven and machine get out of synchronization.

It will be understood that the novel features and principles of this invention may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

What I claim is:

1. In a combined printing machine and oven conveyor drive, a motor having a driving connection with the machine, a motor having a driving connection with the conveyor, means to connect the machine and the conveyor together, to operate both of them by one motor and including differential gearing operably connected to one of the driving connections and an electrically operated clutch for operably connecting the differential gearing to the other driving connection, and means actuated only when both the machine and the conveyor are running, to engage the clutch and operably connect the driving connections together and to deenergize the motor of one driving connection.

2. In a combined printing machine and oven conveyor drive, a first motor for driving the press, a second motor for driving the conveyor, mechanism to connect the motors together for operation of both the machine and the conveyor by one motor and including differential gearing connected to one of the motors and a magnetic clutch for connecting the differential gearing to the other motor, a third motor to operate the differential gearing to thereby synchronize the conveyor with the machine, and a synchronizing detector device in control of the third motor and arranged to stop that motor when the machine and the conveyor are in synchronism.

3. In a combined printing machine and oven conveyor drive, a first motor for driving the machine, a second motor for driving the conveyor, mechanism to connect the motors together for operation of both the machine and the conveyor by one motor and including differential gearing connected to one of the motors and a magnetic clutch for connecting the differential gearing to the other motor, a third motor to operate the differential gearing to thereby synchronize the conveyor and the machine, a synchronizing detector device in control of the third motor and arranged to stop that motor when the machine and the motor are in synchronism, and means actuated only when both the machine and the conveyor are operating, to energize the magnetic clutch and connect the gearing with the first motor and to deenergize the second motor.

4. A combined printing machine and oven conveyor drive comprising a first motor to drive the machine, means to control the feeding of sheets to the machine, means to control the forwarding of sheets from the machine to the conveyor, a second motor for driving the conveyor, means including an electrically operated clutch to connect the first and second motors together for the combined operation of the machine and the conveyor by the first motor, means to engage the clutch only when both motors are running, means to synchronize the press and the conveyor, a synchronizing detector, and a control means actuated by the detector when synchronization exists, to permit feeding sheets to the machine and forwarding them to the conveyor.

5. A combined printing machine and oven conveyor drive comprising a first motor to drive the

machine, means to control the feeding of sheets to the machine, means to control the forwarding of sheets from the machine to the conveyor, a second motor for driving the conveyor, means including a magnetic clutch and a differential gearing to connect the machine and the conveyor together, and means actuated only when both the machine and the conveyor are running to energize the magnetic clutch, and to deenergize the second motor.

6. A combined printing machine and oven conveyor drive in accordance with claim 5 and in which a control is provided in the first motor circuit and is operative to deenergize the magnetic clutch and energize the second motor when the first motor is stopped.

7. A combined printing machine and oven conveyor drive in accordance with claim 5 and having a control circuit for the magnetic clutch, including a centrifugal switch that is closed when the machine is in operation and another centrifugal switch that is closed when the conveyor is in operation, both of which must be closed before the magnetic clutch can be energized.

8. A combined sheet printing machine and oven conveyor drive comprising a motor to drive the machine, means to control the feeding of sheets to the machine, means to control the forwarding of sheets from the machine to the conveyor, another motor for driving the conveyor, means to connect the machine to the conveyor and including a differential gearing connected to one of the motors and a clutch connected to the other motor, a third motor to operate the differential gearing to synchronize the machine and the conveyor, and a synchronizing detector device in control of the third motor and arranged to deenergize that motor when synchronization is accomplished.

9. A combined printing machine and oven conveyor drive in accordance with claim 8 and in which the detector device actuates a timing switch adapted to open a circuit to the third motor to stop it and to close circuits to the means to control the feeding of sheets to the machine and the means to control the forwarding of sheets from the machine to the conveyor, only when the machine and the conveyor are in synchronism.

10. A combined printing machine and oven drive in accordance with claim 8 and in which the detector device is arranged to actuate a timing switch to stop the third motor and to close circuits to the sheet feeding control means and the sheet forwarding control means only when the conveyor is operating in synchronism with the machine.

11. A combined printing machine and oven conveyor drive comprising a motor to drive the machine, means to control the feeding of sheets to the machine, means to control the forwarding of sheets from the machine to the conveyor, another motor for driving the conveyor, mechanism to connect the machine to the conveyor and including a differential gearing connected to one of the motors and a clutch for connecting the gearing to the other motor, a third motor to operate the differential gearing to synchronize the machine and the conveyor, a synchronizing detector device in control of the third motor and arranged to deenergize that motor when synchronization is accomplished, and means actuated only when both the machine and the conveyor are running, to engage the clutch and to deenergize the second motor.

12. A combined printing machine and oven

conveyor drive in accordance with claim 11 and in which a control is provided in the machine driving motor circuit that is operable to release the clutch and to energize the conveyor motor when the machine driving motor is stopped, the detector device being arranged to actuate a switch to stop the third motor and to close circuits to the means to control the feeding of sheets to the machine and the means to control the forwarding of sheets from the machine to the conveyor, only when the machine and the conveyor are in synchronism.

13. A combined printing machine and oven conveyor drive in accordance with claim 11 and in which a control is provided interlocking the circuits of the first mentioned and second mentioned motors, to insure that the second mentioned motor is driving the conveyor before the first motor can be started.

14. A combined printing machine and oven conveyor drive comprising a motor to drive the machine, means to control the feeding of sheets to the machine, means to control the forwarding of sheets from the machine to the conveyor, another motor for driving the conveyor, mechanism to connect the machine to the conveyor and including a differential gearing connected to one of the motors and an electrically operated clutch connecting the gearing to the other motor, a third motor to operate the differential gearing to synchronize the machine and the conveyor, a synchronizing detector device in control of the third motor and arranged to deenergize that motor when synchronization is accomplished, and a control device controlled by the detector device to energize the means to control the feeding of sheets to the machine and the means to control the forwarding of sheets from the machine to the conveyor when synchronization is accomplished.

15. A combined printing machine and conveyor drive comprising a motor to drive the machine, means to control the feeding of sheets to the machine, means to control the forwarding of sheets from the machine to the conveyor, another motor for driving the conveyor, mechanism to connect the machine to the conveyor and including a differential gearing connected to one of the motors and an electrically operated clutch for connecting the gearing to the other motor, a third motor to operate the differential gearing to synchronize the machine and the conveyor, a synchronizing detector device in control of the third motor and arranged to deenergize that motor when synchronization is accomplished, a control device controlled by the detector device to energize the means to control the feeding of sheets to the machine and the means to control the forwarding of sheets from the machine to the conveyor when synchronization is accomplished, and means actuated only when the machine and the conveyor are running to engage the clutch and to deenergize the conveyor motor.

16. A combined printing machine and oven conveyor drive comprising a motor to drive the machine, means to control the feeding of sheets to the machine, sheet forwarding means to carry

sheets from the machine to the conveyor, another motor for driving the conveyor, mechanism to connect the machine to the conveyor and including a differential gearing connected to one of the motors and a magnetic clutch for connecting the gearing to the other motor, a third motor to operate the differential gearing to synchronize the machine and the conveyor, a synchronizing detector device in control of the third motor and arranged to deenergize that motor when synchronization is accomplished, a control device controlled by the detector device to energize the means to control the feeding of sheets to the machine and the means to control the forwarding of sheets from the machine to the conveyor when the synchronization is accomplished, and means actuated only when the machine and the conveyor are running to energize the magnetic clutch and to deenergize the second motor, and control means actuated by the positioning of the conveyor in proper timed relation to the machine, to maintain the magnetic clutch and the sheet feeding controls energized.

17. In a driving mechanism for a printing machine with which an oven having a conveyor is associated, a first driving motor connected to the machine, a second driving motor connected to the conveyor, an adjustable coupling mechanism connected to one of the motors and having a clutch arranged to connect the coupling mechanism to the other motor, a synchronizing motor connected to the coupling mechanism, a synchronizing device having one member rotating in timed relation with the machine and another member rotating in timed relation with the conveyor, and means actuated when both of the said members are in synchronism, to effect engagement of the clutch.

18. In a driving mechanism for a printing machine with which an oven having a conveyor is associated, a first driving motor connected to the machine, a second driving motor connected to the conveyor, an adjustable coupling mechanism including differential gearing having a first connection for driving it by the first motor, and a second connection to drive the conveyor, a synchronizing motor connected to a third connection of the differential gearing and operable to adjust the coupling mechanism, a synchronizing device having one member rotating in timed relation with the machine and another member rotating in timed relation with the conveyor, and means actuated when both of the said members are in synchronism to stop the synchronizing motor.
